COMPRESSIBLE LAMPHOLDERS WITH RECESSED CONTACTS FOR DOUBLE ENDED DISCHARGE LAMPS

John M. Pistey, Fairfield, Conn., assignor to General Electric Company, a corporation of New York

Application August 29, 1955, Serial No. 531,015

9 Claims. (Cl. 339—50)

The present invention relates to lampholders for double-ended electric discharge lamps of the fluorescent type having pre-heated electrodes mounted at the end of the tubular glass envelope. The lampholders of this invention are especially adapted to receive lamps equipped with bases of the type disclosed and claimed in the co-pending application of Eugene Lemmers, Serial No. 380,279, which was filed on September 15, 1953, issued as Patent No. 2,716,739 on August 30, 1955, and assigned to the same assignee as is the present invention.

The novel lamp base of the Lemmers application makes possible the utilization of the usual inlead wires of the lamp electrodes as the lamp terminals, thus eliminating the need for externally protruding contact pins. The inlead wires are recessed within an outwardly projecting electrically insulating part of the base to protect them from accidental contact.

This invention is likewise related to the applicant's co-pending application, Serial No. 452,851, which was filed on August 30, 1954, issued as Patent No. 2,716,738 on August 30, 1955, and assigned to the same assignee as is the present invention. Fluorescent lamps are supported at each end by a lampholder, and the smaller the size of a lampholder from its lamp engaging face to its back face, the shorter the over-all distance will be between the backs of the lampholders. Thus, in using the compact lampholders embodying my invention, lamp fixtures for supporting the lamps may be reduced in size, thereby effecting a cost saving for the lamp fixture manufacturer as well as making it possible to increase the illumination by installing more fixtures for a given ceiling length and reducing dark spots between the lamps.

A set of lampholders embodying my invention comprises a stationary holder and a compressible holder in axial alignment. The compressible lampholder has a spring-biased retractable cover so that one end of the lamp may be forced into the holder by pushing against the cover while the other end of the lamp may be brought into position in alignment with the opposite stationary lampholder. Hence, when the lamp is released it will be compressed between the two lampholders.

A feature of the lampholders of this invention is a pair of spring-pressed, closely spaced, insulated electrical contacts recessed within the holder and having lamp terminal engaging portions which diverge outwardly before a lamp base is inserted in the holder and which are moved by the insertion of the lamp base into the holder. As a result of a cam action between the holder contacts and the lamp terminals, each of the contacts makes a wiping electrical contact with a terminal of the lamp. Another advantage is that the spring members and contacts of the holders are so arranged that the cover with its lamp base-receiving cavity in the front face may be assembled in either its horizontal or its vertical position. This is a desirable quality for a lampholder that is to be used in a fixture with tandem lamps where a pair of lampholders are to be mounted back to back on a supporting plate.

2

This invention makes it possible to stagger the fastening screws for each of the back-to-back lampholders while retaining a particular position of the lamp base-receiving cavity in the front face of each lampholder so that it is possible to remove a single lampholder and service it without disturbing the position of the other.

The primary object of this invention is to provide a lampholder for tubular lamps having bases with recessed terminals so that the lamps may be mounted by longitudinal motion in the lampholders while the size of each lampholder from front to back is retained at a minimum dimension.

A further object of this invention is to provide lampholders with pivoted contacts which are recessed in the front face of the holder for receiving the recessed terminals of a lamp base.

A further object of this invention is to provide a lampholder with pivoted contacts which normally diverge outwardly from each other when the lamp is removed from the holder.

A further object of this invention is to provide a fluorescent lampholder with suitable spring means which may be so positioned that it is possible to select either a horizontal or a vertical position for the lamp base-receiving cavity in the front face of the holder.

My invention will be better understood from the following description taken in connection with the accompanying drawings and its scope will be pointed out in the appended claims.

Figure 1 is a side elevational view showing the novel lampholders of the present invention and a lamp having bases with recessed terminals mounted in the holders.

Figure 2 is a view similar to that of Figure 1 with the lampholders shown in cross-section; the view of the left-hand lampholder being taken on the lines 2—2 of Figure 3.

Figure 3 is a front view of the left-hand lampholder of Figure 2.

Figure 4 is a front view of the right-hand lampholder of Figure 2.

Figure 5 is an end view of the lamp base which is to be mounted in the lampholders embodying this invention.

Figure 6 is an exploded view of the left-hand lampholder of Figure 2.

Figure 7 is an exploded view of the right-hand lampholder of Figure 2.

Figure 8 is a cross-sectional view similar to that of the right-hand lampholder of Figure 2 except that the lamp base has been removed from the holder.

Figure 9 is a rear view of the cover member of Figure 6 with one of the contact members located therein.

Figure 10 is a cross-sectional view of a modification of the stationary lampholder of Figure 7.

Figure 11 is a view similar to Figure 10 showing a lamp supported therein.

Figure 12 is an exploded view of the lampholder of Figure 10.

Referring in detail to the drawing and particularly to Figure 1, the lamp has a tubular glass envelope 10 provided with bases 11 and 12 attached to its ends, and is supported between a pair of lampholders 13 and 14 which are to be attached to a suitable support which may be part of a lighting fixture. The compressible holder 13 is shown in cross-section at the left-hand side of Figure 2 as well as in the exploded view of Figure 6, while the stationary holder 14 is shown in cross-section at the right-hand side of Figure 2 and in the exploded view of Figure 7. The parts which comprise the holder 13 may be best explained with reference to Figure 6 which shows a recessed base member 16 of suitable molded insulating material having an open end 17 for receiving an insulating cover 18 that is adapted to move back and forth in the

base. Four equally spaced notches 19 are located around the periphery of the cover to mate with four similar guide ribs 20 on the interior of the side walls of the base. A metal cup 21 fits over the main portion of the base 16 and is fastened therewith when the lanced tangs 22 spring into the slots 23 of the base in a well-known manner. An outer flange 24 of the cup serves as a limit means to prevent the cover 18 from becoming separated from the base.

The front face of the cover 18 has a non-circular cavity 25 for receiving the lamp base 11 of Figure 5. A central projection 26 is located in the cavity with a pair of opposite grooves 27 formed therein. A pair of contacts 30 are located behind the cover 18 and they each comprise a lamp terminal-engaging portion 31, a pair of spring seats 32 and a pair of fulcrums 33. Looking at Figure 9 which is a back view of the cover 18, there is shown a pair of depressions 35 each having an opening 36 through which the terminal engaging portion 31 of the contact extends. The fulcrums 33 are located adjacent the side of the cover while the coil springs 37 bear against the bottom wall of the base and the spring seats 32. The portion 31 of the contact is guided in the groove 27 of the projection 26 of the cover as well as being insulated from the other such portion. Because of the relative positions of the fulcrums 33 and the portions 31 of the contact, the springs 37 normally pivot the contacts slightly away from the projection 26 when the lamp base is removed. Thus, when the lamp is being assembled in the holder, the recessed terminals of the lamp base will wipe against the portions 31 of the contacts to make good electrical connection therebetween. The symmetry of the four coil springs 37 in the base 16 make it possible to adjust the position of the cover 18 so that the cavity 25 may be in either its horizontal or its vertical position. A lead wire 38 having a ring type terminal 39 may be inserted through an opening (not shown) in the back of the base and fitted over the spring seat 40 therein of one of the springs of each related pair of springs 37 so that the holder may be connected as part of an electrical circuit. The back of the base 16 has a pair of mounting holes 41 for receiving fastening screws (not shown) so that the holder may be attached to a supporting surface.

The lamp bases 11 and 12 are identical so that reference will be made to only base 11 of Figures 2 and 5. This base comprises an annular metal shell 42 and a disk 43 of electrically insulating material, such as an organic plastic. The inner rim of the shell 42 is imbedded in the periphery of the disk 43 to mechanically join these elements together as shown in Figure 2. The base 11 is secured to the end of the glass envelope 10 by a body of basing cement 44. The disk 43 has an oval-shaped embossment 45 which is to be fitted in the cavity 25 in the front face of the cover 18. A passage 46 extends completely through the disk so that the wire inleads 47 and 48 connected to electrode 49 of the lamp may be brought outwardly to constitute recessed electric terminals for the lamp. Thus, both the contacts 30 of the lampholder 13 and the terminals 47 and 48 of the lamp bases 11 and 12 are recessed so that they may not be touched accidentally in the ordinary handling of the lamp incident to its insertion and removal as described above.

The stationary lampholder 14 of Figures 2, 7 and 8 has a recessed base 50 of molded phenolic or other suitable electrical insulating material and an insulating cover 51 fastened by screw means 52 over the face of the base. The appearance of the cover 51 is similar to that of cover 18 of Figure 6 in that it has an oval-shaped cavity 53 for receiving the embossment 45 of a lamp base. In the cavity 53 is a projection 54 having opposite grooves 55. The L-shaped contacts 56 are each positioned on an elongated spring 57 of strip material having ends 58 which are bent under to form spring feet. The long leg 59 of the contact has a rounded free end 60 which is confined between the base and cover to serve as the fulcrum for the contact. Each contact extends through a slot 61 in

the cover with the short leg 62 of the contact guided in the groove 55 in the projection 54. As shown in Figure 8, the contacts 56 diverge outwardly from the projection 54 when the lamp is removed so that there is a double wiping action between the holder contacts and the lamp terminals.

The base 50 is of unique design in that the parallel springs 57 may be located in either a horizontal or vertical position. This arrangement is afforded by the symmetry of the group of four partitions 63 and the central square-shaped depression 64. The mid-portion of each spring 57 is adapted to be seated in the depression 64 adjacent the side wall. The lead wire 65 has a U-shaped terminal 66 that supports one end of the spring 57. Three notches 67 are made in the sides of the base so that the pair of lead wires of the holder may be shifted to accommodate the different positions of the springs 57. The terminals 66 are seated in the base so that their top surfaces are flush with a related supporting surface for the opposite end of the spring. The partitions 63 each contain a threaded opening 68 so that the cover 51 may be fastened in either its horizontal or vertical position.

In the modification of the stationary lampholder 70 of Figures 10-12, a major change has been made by substituting a pair of contacts 71 of strip material which have an integral spring portion 72 for giving double wiping action, as well as a locating ring 73 and a terminal end 74 so that a bare lead wire may be crimped thereto. In Figure 12 the holder 70 is shown as comprising a recessed base 75 and a cover 76 assembled therewith by suitable screw means 77 of Figure 12. The cover 76 is substantially the same as cover 51 of Figure 7, except that the opening 78 for receiving the contact 71 is wider. The locating ring 73 fits over the stud 79 in the base and a depression 80 in the base accommodates the terminal end 74 of the contact adjacent the lead wire-receiving opening 81 in the side wall of the base.

The free end 82 of the spring portion 72 of the contact is slightly bent, as shown in Figures 10 and 11, to receive the rounded projection 83 of the cover which clamps the end 82 to the base. When the lamp is removed from the holder, the contacts 71 assume the divergent position shown in Figure 10. Thus, in inserting the lamp in the base the lamp terminals cam the contacts of the lampholder toward the central projection of the cover to give a double wiping action between the contacts and terminals. It will be readily appreciated by one skilled in this art that this stationary lampholder 70 has been reduced to the least number of parts, namely, a base and a cover with a pair of contact members and a pair of fastening screws for holding the parts assembled.

Accordingly, having described my invention of a novel set of lampholders having recessed contacts which are pivotally mounted therein, it will be readily apparent to one skilled in this art that I have been able to reduce the depth of these lampholders to a minimum practical dimension. I have likewise made it possible to assemble the covers of the modifications shown in Figures 1-9 in either a horizontal or a vertical position with respect to the front face of the base. While in the modification of Figures 10-12 of a stationary lampholder I have reduced the number of parts to an absolute minimum because each contact has an integral spring portion, locating ring and terminal end.

Modifications of this invention will occur to those skilled in this art and it is to be understood, therefore, that this invention is not limited to the particular embodiments disclosed but that it is intended to cover all modifications which are within the true spirit and scope of this invention.

What I claim as new and desire to secure by Letters Patent of the United States is:

1. A fluorescent lampholder comprising a hollow housing having a recessed base and a cover member, said cover member having a cavity in its outer face for receiving a lamp base, a central projection within the cavity,

and a pair of pivotally mounted contact members located in the housing, each contact fulcrumed adjacent the side of the housing and extending through an opening in the cover to lie within a common plane on opposite sides of the said projection, and spring means in the base for forcing the inner ends of the contacts to pivot away from the projection so that they normally diverge outwardly when the lamp is removed.

2. A lampholder comprising a hollow housing having a recessed base and a cover member, a non-circular cavity in the outer face of the cover for receiving a lamp base, and a central projection within the cavity having a pair of grooves on its opposite sides, a pair of pivotally mounted contact members located within the housing, each fulcrumed adjacent the side of the housing and extending through an opening in the cover to lie within the groove, on the side of the projection so that the contacts will be insulated from each other and guided in its movement by the said projection, and spring means in the base which bear against the contacts so that their inner ends are pivoted to a divergent position when the lamp is removed whereby a wiping action is present between the said contacts and the terminals of the lamp base as the lamp is inserted in the holder.

3. A lampholder comprising a hollow housing having a recessed base and a cover member, the cover being guided for reciprocating movement in the base, and abutment means for holding the base and cover assembled, a cavity formed in the front face of the cover for receiving a lamp base, the cavity having a central projection therein with a groove formed on opposite sides of the projection, a pair of contacts located in the housing and extending through openings in the cover to lie within the grooves of the said projection, the opposite end of each contact being fulcrumed adjacent the side wall of the housing, and a pair of springs for each contact seated on the base and bearing against the underside of the contact at spaced points, the fulcrum point of each contact being below the free end of the contact so that when the lamp base is removed from the holder the free ends of the contacts tend to pivot away from the projection.

4. A lampholder comprising a hollow housing having a recessed base and a cover member fastened thereto, a cavity in the front face of the cover for receiving a lamp base, and a central projection located in the cavity, a pair of L-shaped contacts of strip material in the housing and extending through an opening in the cover with the short legs of the contacts separated by the projection

while the opposite ends of the contacts are fulcrumed away from the center of the housing so that the contacts move in a common plane, a spring member supported on the base and bearing against the mid-section of the long leg of each contact to normally pivot each contact slightly away from the projection, the said springs comprising a member of strip material where the ends are doubled under to serve as the spring portions.

5. A lampholder comprising a hollow housing having a recessed base and a cover member, a cavity in the front face of the cover for receiving a lamp base, and a central projection located in the cavity having a groove formed on its opposite sides, a pair of contacts of strip material positioned in the housing, each contact comprising an offset spring portion having a free end held between the base and cover, a V-shaped contacting portion which extends through the cover and is located in the groove of the said projection, and an integral portion for locating the contact in the base and making connection with a bare lead wire.

6. A lampholder as recited in claim 5 wherein the integral portion comprises a locating ring having a terminal which may be crimped over a bare lead wire.

7. An article of manufacture of a contact of strip material for a fluorescent lampholder comprising an offset spring arm joined with a V-shaped contacting portion and an integral portion of a locating ring with a terminal for making connection with a bare lead wire.

8. A fluorescent lampholder comprising a hollow housing with a cavity in its front face for receiving a lamp base, a central projection within the cavity, and a pair of pivotally mounted contact members located in the housing, each contact fulcrumed adjacent the side of the housing and extending through an opening within the cavity to lie in a common plane on opposite sides of the said projection, and spring means bearing against the contacts for forcing the adjacent ends of the contacts to pivot away from the projection so that they normally diverge outwardly when the lamp is removed.

9. A lampholder as recited in claim 8 wherein there is a groove on opposite sides of the projection to support and guide the movement of the adjacent ends of the contacts when they are engaged by a lamp.
